A. H. MIDGLEY

TELEPHONIC RECEIVER

Filed August 25, 1925

Inventor
Albert Henry Midgley
By *Henry Midgley* att.

UNITED STATES PATENT OFFICE.

ALBERT HENRY MIDGLEY, OF UXBRIDGE, ENGLAND.

TELEPHONIC RECEIVER.

Application filed August 25, 1925, Serial No. 52,431, and in Great Britain August 26, 1924.

This invention comprises improvements in and connected with telephonic receivers. In these instruments it is very important, in order to obtain good reception, that the pole pieces of the magnets be very securely and solidly held in place. This requirement is possibly of greater importance in the so-called loud speakers than it is in the ordinary telephone ear piece receivers, but advantage is to be obtained in every case where the pole pieces are secured in the manner referred to. It is of further importance, in considering any means to be adopted for achieving this end, that such means shall be capable of simple and accurate reproduction in large numbers and of being easily and reliably assembled in manufacturing instruments according to modern methods of production.

20 The object of the present invention is to provide a magnet structure and means for securing the pole pieces therein which will satisfy all the requirements set out in the foregoing paragraph.

25 According to this invention, the pole pieces are secured in a suitable magnet structure by wedges adapted for operating so that the wedging action does not upset the accurate dispositioning of the pole pieces. Furthermore, the pole pieces may be wedged against respective yoke pieces disposed between the ends of parallel bar magnets, these yoke pieces giving a path of low magnetic resistance from the bars to the pole pieces and producing a solid magnet structure adapted for withstanding the powerful wedging action exerted in securing the pole pieces.

30 In order to enable this invention to be readily understood, reference is made to the accompanying drawing illustrating two examples of practical embodiments of the invention, in which drawing:—

Figure 1 is a central vertical section of the base portion of a loud speaker containing a magnet structure and pole pieces secured therein in accordance with this invention.

Figure 2 is a horizontal section on the line II—II of Figure 1.

Figure 3 is a perspective view of the magnet structure into which the pole pieces are fitted and secured.

Figure 4 is a perspective view of two pole pieces removed from the structure seen in

Figures 1 to 3, one of these pole pieces being seen furnished with the usual magnet coil whilst the other has had its coil removed, so that such coil is only indicated by dotted lines.

60 Figure 5 is a perspective view of the wedging means employed for securing the pole pieces.

Figure 6 is a sectional elevation illustrating the wedging of a modified form of pole piece against a modified form of yoke piece.

65 Referring to Figures 1 and 2, the loud speaker comprises a base *a* on which is mounted a diaphragm *b* in operative relation with the poles of pole pieces *c*, the diaphragm being shielded by a cover *d* formed with a spigot *e* for the fitting on of the stem of a horn or sound amplifier. The magnet structure see also Figure 3, comprises parallel bar magnets *m* with stout yoke pieces *n* *n'* bolted between them by bolts *o* *o'*, the ends of the bolt *o* being formed with centre recesses to act as centre bearings for the centre points of screws *q*. It will be seen that this magnet structure is pivotally mounted at one end on the centre bearings aforesaid, whereas the other end is supported by a prolongation *s* of the yoke piece *n'* resting upon a bow spring *t* supported by nuts on screws *v*. Thus the pole pieces *c* are capable of being adjusted nearer to or further from the diaphragm *b* by a screw *w*, the turning of which either depresses the magnet structure about its pivot and against the resistance of the spring *t* or 70 permits the latter to elevate the magnet structure. This construction and arrangement of magnet is fully described and claimed in my United States Patent No. 1,582,770, dated April 27, 1926.

75 The present improvements, as stated above, relate to the fixing of the pole pieces. It will be observed from Figures 2 and 3 that the inner ends of the yoke pieces *n*, *n'* are of reduced width so as to leave spaces 80 between them and the bar magnets *m*, and it is to these reduced ends that the pole pieces *c* are secured.

85 The pole pieces *c* are assemblages of laminæ, their upper portions being appropriately formed for receiving magnet coils 2 in the usual manner, and their lower portions being formed with enlargements presenting on one side upper and lower inclined or wedge surfaces 3, 4. The opposite or outer side of 90

the said lower portions may be planar for fitting against planar surfaces of the ends of the yoke pieces n , n' or they may also be formed with wedge surfaces as hereinafter described. Two rectangular pieces 5, 6 of brass or other suitable material, seen separately in Figure 5, are formed with bevelled edges corresponding with the wedge surfaces 3 and 4, and with holes at the centre, the hole in the piece 5 being screw threaded.

The magnet structure being suitably supported in the manner above described, the pole pieces c are inserted into the gap between the yokes n , n' with their planar faces against the end faces of the yoke pieces. The wedge piece 5 is inserted between the wedge surfaces 3 and the wedge piece 6 is inserted between the wedge surfaces 4, a screw 7 being then passed through the piece 6 and screwed into the piece 5. Before tightening up the screw 7, the pole pieces are adjusted so that the pole tips are appropriately disposed in relation to the diaphragm b whereupon the screw 7 is tightened which effects a powerful drawing together of the wedge pieces and consequent pressing of the pole pieces against the yoke pieces n , n' with such force as to secure the pole pieces strongly in their adjusted position without any danger of shifting.

When the pole pieces c are formed with wedge faces 3, 4 on one side only of their lower portions, the planar faces on the opposite side permit of the pole pieces being secured in desirably adjusted positions as explained. However, this may not be necessary, as for example in telephone ear pieces. In such cases, both sides of the lower portions of the pole pieces may be formed with wedge faces, as seen for example in Figure 6 in which the outer sides of the pole pieces are formed with wedge faces 3^a , 4^a corresponding with the wedge faces 3, 4 on the inner sides. The end faces of the yoke pieces are grooved giving corresponding wedge faces as seen in this figure. Upon tightening up the screw 7 in this construction, the pole pieces c will be rigidly secured by the wedging action on both sides, the position of pole pieces c being a fixed one, owing to the grooved end of the yoke pieces n , n' .

As seen clearly in Figure 4, the assemblages of laminæ may be bound around the bottom and sides with a brass or other non-magnetic strip 8. This strip may be enlarged and shouldered at 9 to provide a seating for the spools of the coils 2 when these latter are passed on to the pole pieces. The ends of the strip 8 Figure 4 may be bent over as at 10, to form abutments or clipping means for engaging the upper flange of the

spool and retaining such spool upon the seating provided by the shoulders 9.

I claim:—

1. Telephone magnet comprising a robust magnet structure, individual pole pieces insertable into said structure, wedge devices engaging each of said pole pieces for securing same at the desired distance apart in said structure, and tightening means operatively engaging said wedge devices.

2. Telephone comprising an adjustably mounted magnet structure, individual pole pieces, and mechanically operated wedge devices for securing the latter in spaced relation in said structure.

3. Telephone magnet comprising a parallel magnet structure, individual pole pieces disposed in the middle of said structure, and mechanically operated wedge devices securing the pole pieces in spaced relation in the structure.

4. Telephone magnet comprising parallel bar magnets, stout yoke pieces spacing said bar magnets, robust fixing means passing through said magnets and yoke pieces, pole pieces inserted between said yoke pieces, wedge devices inserted between said pole pieces, and mechanical tightening means operatively engaged with said wedge devices.

5. Telephone magnet comprising two separate pole pieces fixed in spaced relation in the magnet structure by opposed wedge devices operatively engaged by a mechanical adjustment.

6. Telephone comprising a magnet structure composed of bar magnets spaced apart at the ends by yoke pieces, pole pieces inserted between the inner faces of the yoke pieces, and opposed wedge devices cooperating with wedge faces of said pole pieces for fixing the latter in said structure.

7. Telephone comprising a magnet structure composed of a pair of parallel bar magnets, stout yoke pieces spacing said bars apart at respective ends, bolts bolting said bars and yoke pieces together, polar formations at the inner ends of said yoke pieces, pole pieces adapted to fit against respective polar formations, and wedge devices inserted between said pole pieces and operative to force the latter against the said polar formations substantially as set forth.

8. Telephone comprising a frame-like magnet structure, the side members being permanent magnets and the end members being yokes, pole pieces abutting against respective yokes said pole pieces being spaced apart and forced against said yokes by opposed wedge devices engaging double wedge faces on said pole pieces.

ALBERT HENRY MIDGLEY.
